DESIGN FOR A JAR

Glen Robert Carpenter, Chicago, Ill.

Application October 18, 1937, Serial No. 72,294

Term of patent 14 years

To all whom it may concern:

Be it known that I, Glen Robert Carpenter, a citizen of the United States, residing at Chicago, in the county of Cook and State of Illinois, have invented a new, original, and ornamental Design for a Jar, of which the following is a specification, reference being had to the accompanying drawing, forming a part thereof.

In the drawing:

Figure 1 is a perspective view of a jar embodying my design.

Figure 2 is a side elevational view showing the jar of my design resting on one of its bases.

Figure 3 is a side elevational view showing the jar of my design resting on the other of its bases.

I claim:

The ornamental design for a jar substantially as shown.

GLEN ROBERT CARPENTER.
